UNITED STATES PATENT OFFICE.

JEAN HEPPEL, OF NEWARK, NEW JERSEY.

AIRSHIP.

1,390,993.

Specification of Letters Patent. Patented Sept. 20, 1921.

Application filed September 26, 1918. Serial No. 255,763.

To all whom it may concern:

Be it known that I, JEAN HEPPEL, a subject of the Emperor of Germany, residing at Newark, in the county of Essex and State of New Jersey, have invented a new and useful Airship, of which the following is a specification.

This invention relates to improvements in dirigible air ships in which atmospheric air is used as a ballast, the construction being of a slightly different character than that in my co-pending application filed Sept. 5th, 1918, Ser. No. 252,737.

The principal object of the present construction is the even distribution of the ballasting fluid throughout the full length of the ship.

Another object of the present invention is the provision of an air ship which is subdivided into a plurality of compartments within each of which is arranged a ballonet and a means for charging the compartments with a ballasting fluid.

To enable others skilled in the art to more readily understand the present invention, the following specification should be considered in connection with the attached drawings, wherein there is shown the preferred embodiment of the idea.

Similar letters of reference indicate like parts throughout the several views, in which Figure 1 is a longitudinal cross section showing all of the principles of the invention; Fig. 2 is a transverse section on line 2—2; Fig. 1 and Fig. 3 is a side view of one of the ballonnets.

Referring more in detail to the drawings, reference character 1 indicates a rigid outside framework which may be made up of rods, girders, etc., into any desirable shape, 2 illustrates an air well extending longitudinally from the fore to the aft end of the framework. The space between the framework 1 and the air well 2 is divided into a plurality of compartments by plates 3; each compartment is adapted to contain a ballonet 4 which is charged with a buoyant fluid.

The air well 2 is provided with a plurality of openings 5 which communicate with passages 6 arranged between the compartments and the ballonnets. Outlets 7 are provided at the lower end of these passages for admitting air between the side walls of the passages and the side walls of the ballonnets.

Suitably supported within the well 2 and

driven in any desirable manner, propellers 8 arranged adjacent the fore and aft ends of the well. Positioned between the propellers are valve members 9 and 10 operated by cables or chains 11 from a car suspended beneath the framework.

When it is desired to launch the air ship after the ballonnets have been charged, the aft valve 10 is operated to close the passage 65 through the air well and the fore propeller put into motion. This forces a charge of air under considerable pressure, into the compartments between the walls of the ballonnets, slightly compressing the latter. When a sufficient amount of air has been accumulated in the compartments to ballast or counter-balance the lifting effect of buoyant fluid within the ballonnets, the propeller is stopped and the fore valve closed, thereby holding 75 the air within the vessel. The ship may then be moved with considerable ease to the outside of its hanger when free from all obstacles, the valves are turned to open the passage through the air well and allow the 80 trapped air to escape. The re-expansion of the ballonnets, together with the suction created within each compartment caused by the revolutions of the rear propeller within the air well, will remove all of the ballasting 85 air within the compartments.

Many changes could be made in the above construction and many apparently widely different embodiments of this invention could be made without departing from the scope 90 thereof, it is intended that all matter contained in the above description or shown in the accompanying drawing shall be interpreted as illustrative and not a limited sense.

What I claim is:

1. An air ship comprising a rigid frame structure divided into a plurality of longitudinally arranged compartments and having an air well extending centrally and longitudinally therethrough, bags within each 100 compartment and arranged about the air well for containing a buoyant fluid and pockets arranged about each of said compartments for maintaining a charge of heavy fluid within each pocket to ballast the ship, 105 means for admitting the heavy fluid within the pockets and means for releasing said fluid.

2. An air ship comprising a rigid frame structure divided into a plurality of longitudinally arranged compartments and having an air well extending centrally and lon-

5 longitudinally therethrough, bags within each compartment and arranged about the air well for containing a buoyant fluid, pockets arranged about the air well and between the 10 bags for maintaining a charge of heavy fluid within each pocket to ballast the ship and means for releasing the charge of heavy fluid.

15 3. An air ship comprising a rigid frame structure divided into a plurality of longitudinally arranged compartments and having an air well extending centrally and longitudinally therethrough, bags within each compartment and arranged about the air well for containing a buoyant fluid and pockets about the bags for trapping within the compartments ballasting fluid.

20 4. An air ship comprising a rigid frame structure divided into a plurality of longitudinally arranged compartments and having an air well extending centrally and longitudinally therethrough, bags within each compartment and arranged about the air well for containing a buoyant fluid said air well provided with openings communicating 25 with the compartments, air passages ar-

30 ranged about the bags and within the compartments, and means for forcing a charge of air into the air passages to counterbalance the lifting effect of the buoyant fluid.

35 5. An air ship comprising a rigid frame structure divided into a plurality of longitudinally arranged compartments and having an air well extending longitudinally therethrough, bags within each compartment 40 for containing a buoyant fluid, said air well provided with openings adjacent the compartments, conduit pipes arranged within the compartments in communication with the openings in the air well, and means for forcing a charge of air from the air well into the conduit pipes and finally into the compartments and about the said bags to counterbalance the lifting effect of the buoyant fluid.

45

In testimony whereof I affix my signature in the presence of two witnesses.

JEAN HEPPEL.
